[57] CLAIM

The ornamental design for an exterior film-feeding camera, as shown and described.

DESCRIPTION

FIG. 1 is a top, front and left side perspective view of an exterior film-feeding camera showing my new design;

FIG. 2 is a reduced front view of the exterior film-feeding camera shown in FIG. 1;

FIG. 3 is a back view thereof.

FIG. 4 is a left side view thereof.

FIG. 5 is a right side view thereof.

FIG. 6 is a top view thereof.

FIG. 7 is a bottom view thereof; and,

FIG. 8 is a top, front and left side perspective view thereof, the broken lines shown are for illustrative purposes only and form no part of the claimed design.
